UNITED STATES PATENT OFFICE.

JOHN P. HISLEY, OF SYRACUSE, NEW YORK.

HAME.

SPECIFICATION forming part of Letters Patent No. 230,939, dated August 10, 1880.

Application filed October 26, 1877.

To all whom it may concern:

Be it known that I, JOHN P. HISLEY, of the city of Syracuse, in the State of New York, have invented new and useful Improvements in 5 Harness-Hames, of which the following, taken in connection with the accompanying drawings, is a full, clear, and exact description.

This invention relates to harness-hames composed of cast metal; and it consists in certain 10 peculiarities in its detail construction whereby its weight is reduced and at the same time its stability augmented, substantially as hereinafter fully described.

In the accompanying drawings, Figure 1 is 15 a front view of my improved hame; Fig. 2, a rear view of same; Fig. 3, an enlarged transverse section on line y y , Fig. 2; Fig. 4, an enlarged transverse section on line x x , Fig. 2; Fig. 5, a view of the hame-strap loop 20 detached. Fig. 6 shows the end of the hame as cast for attaching the hame-strap loop by cold-shutting or clinching around the bar thereof a prong cast onto the hame, and Fig. 7 a side view of a hame cast with an eye in its end to 25 serve as a hame-strap loop.

Similar letters of reference indicate corresponding parts.

A is the hame, of a form and dimensions in some respects similar to those hitherto made 30 of wrought-iron.

The turret or rein-guide r and tug-loop l 35 may consist of the same metal and cast with the hame in one piece, or they may be of different material and the hame cast onto the same.

In order to reduce the weight of the hame, and at the same time augment its rigidity without depriving it of the usual external form of metallic hames, and thus adapt it for 40 the usual leather covering, I make the hame

of a concavo-convex form in cross-section of its body by providing it with a longitudinal concavity, c , on the under side. This concavity is partly filled, as shown at a a' , to re-enforce the hame at the junction therewith 45 of the turret and tug-loop and prevent undue shrinkage thereat during the cooling of the casting incident to said appendages cast thereon.

The hame-strap loop s may either consist of 50 an eye or aperture cast in the end of the hame, as shown in Fig. 7 of the drawings, or constructed as shown in Fig. 5 of the drawings, and attached to the hame either by casting the end of the hame loosely around the bar v 55 of the loop, or, when the hame is composed of malleable cast-iron, by cold-shutting or clinching around the bar of said loop a prong, e , cast on the ends of the hame, as shown in Fig. 6 of the drawings. 60

That portion of the bar v of the loop s which is embraced by the end of the hame is contracted toward its center and provided with a shoulder, n , at each end to secure it in its proper relative position on the hame. 65

Having thus described my invention, what I claim is—

The concavo-convex hame A, re-enforced at the turret and tug-loop by fillings a a' of the concavity c , substantially as and for the purpose shown and described. 70

In testimony whereof I have signed my name and affixed my seal, in the presence of two attesting witnesses, at Syracuse, State of New York, this 5th day of September, 1877. 75

JOHN P. HISLEY. [L. S.]
